UNITED STATES PATENT OFFICE.

ABRAHAM BALINKY, OF NEW YORK, N. Y.

EMBROIDERING-MACHINE.

1,371,838.

Specification of Letters Patent. Patented Mar. 15, 1921.

Application filed June 11, 1920. Serial No. 388,227.

To all whom it may concern:

Be it known that I, ABRAHAM BALINKY, a citizen of the United States, residing in the city, county, and State of New York, 5 have invented certain new and useful Improvements in Embroidering-Machines, of which the following is a specification.

My invention relates to embroidering machines and particularly to that type of embroidery machine adapted to be operated or guided by hand for embroidering the desired material.

An object of my invention is to provide an embroidering machine which includes 10 embroidery means and means for feeding the machine; a further object being to operate the feeding means from the embroidery means.

Another object of my invention is to provide a feeding means for a hand embroidering machine which will positively feed the machine.

Another object of my invention is to provide a feeding means for a hand embroidering machine which has a member in contact 25 with the material to be embroidered which is given intermittent motion to feed the machine; a further object being to effect the feed on the up stroke of the embroidering 30 needle.

Another object of my invention is to provide feeding means for a hand embroidering machine which includes mechanism for adjustment of the amount of feeding action; 35 a further object being to operate such a feeding means from the embroidering means.

Another object of my invention is to provide an embroidering machine having means for feeding the machine by contact of a 40 member with the material to be embroidered and means for breaking such contact while the needle is in the material.

Another object of my invention is to provide an embroidering machine in which the 45 needle is reciprocated along and held from movement out of its axial line and in which the feeding is positively effected by means other than the needle in order to avoid spreading of the fibers of the material; a 50 further object being to provide such a hand embroidering machine with a source of power for operating the mechanism while the machine is guided by hand.

In the drawings in which similar refer- 55 ence characters indicate like parts, Figure 1

is an elevational view of a hand embroidering machine embodying my invention.

Fig. 2 is a partial view taken from the opposite side of the device shown in Fig. 1.

Fig. 3 is a view of a detail of the driving 60 mechanism of the device shown in Fig. 1.

Fig. 4 is a cross-section on line 4-4 of Fig. 3.

Fig. 5 is a side view of the parts shown in Fig. 3.

Fig. 6 is a cross-section on the line 6-6 of Fig. 1.

Fig. 7 is a cross-section on the line 7-7 of Fig. 1.

Fig. 8 is an elevational view of a slightly 70 different embodiment of my invention from that shown in Fig. 1.

Fig. 9 is a view taken from the opposite side of Fig. 8 with parts broken away.

Fig. 10 is a view with parts broken away 75 of the construction shown in Figs. 8 and 9 in depressed position.

Fig. 11 is a partial sectional view through the adjusting nut 27.

Fig. 12 is a detail view.

Fig. 13 is a sectional view on line 13-13 of Fig. 9.

In the embodiments of my invention illustrated in the drawings, a frame is provided that consists of the tubular member or operating bar guide 1, surrounded by a second tubular member or base portion 2 which carries or is formed with a foot 3 adapted to contact with the material to be embroidered. The foot 3 carries a web portion 4 90 upon which other parts may be mounted as hereinafter described. Mounted for reciprocation within the frame member 1 is a needle operating bar 5 but the needle operating bar 5 may be otherwise mounted upon 95 the frame. A needle 6 is fixed relatively to the operating bar 5 for example, as shown in Figs. 1 and 8, by being held within a recess by means of a screw 7 passing through a slot 7' in the wall of the frame.

In the embodiment shown in Figs. 8 to 13 contact between screw 7 and the top of the slot 7' limits the upward motion of the operating bar. Surrounding the needle is a thread gripping member 8 to which is attached an upwardly extending rod 9 which is connected to the actuating member or handle 10 and which is of such a length that when the actuating member, which is slidably mounted on the operating bar 5 is 110

pushed down as far as it will go upon the bar 5, the thread gripping member is free of the lower end of the operating bar 5, as shown in Figs. 2 and 10. But when the actuating member 10 is drawn upward it slides upward on the operating bar 5, as shown in Fig. 9 and draws the member 8 up against the bottom of the operating bar 5 to grip the thread between itself and the lower end 10 of the operating bar and lies in the position shown in Figs. 1 and 9. Upon the web 4 of the presser foot there are mounted by means of the pivot 14 for rotary reciproca- 15 tion or oscillation two members 15 and 16. A member 18 is pivoted to the lower end of the member 16 by the pivot 17. The member 18 has an arm 19 which is guided by the lug 20' in the construction shown in Figs. 1 to 7 and in the slot 20 (see Fig. 13) in the 20 construction shown in Figs. 8 to 13 so that the swinging motion of the pivot 17 will re- result in a backward and forward movement of the feeding member 18 to which is at- 25 tached a material contacting feeding mem- ber 21, which is preferably of flexible ma- terial having a serrated edge 22 and pro- vided with a notch 22' to prevent it from interfering with the operation of the needle as shown in Fig. 12. A projection 30 on 30 the operating bar 5 engages in a slot 31 in the operating member 15 so that reciproca- 35 tion of the operating member causes a swinging of the member 15. In the construction shown in Figs. 1 and 2 the mem- ber 15 is provided with a pin 50 fitting in a slot in engaging member 51 and holding the engaging member 51 in place upon the mem- ber 15. Engaging member 51 has a threaded 40 extension 52 which passes through a lug 53 on the member 15 and is provided with a nut 54. A spring 55 surrounding the extension 52 keeps the engaging member 51 in its lower- most position. A finger 56 on the link 16 45 engages within a notch 57 in the engaging member 51. In the construction shown in Figs. 1 and 2 the feeding member 22 rides over a disengaging member 58 formed on the presser foot so that when the needle is pressed down and the feeding member 22 50 is drawn back, as shown in Fig. 2, contact will be broken between the feeding member and the material and the amount of feed for each stroke of the needle will be mea- 55 sured by the amount of movement after the feeding member 22 is slid beyond the lower edge of the contact breaking member 58 by the members 15, 16 and 18. In order to vary this amount of movement of the feed- 60 ing member 22 the nut 54 is rotated to change the angular relation of the members 15 and 16 so that the feeding member 22 will slide off of the member 58 at an earlier or later time during the stroke of the needle.

In the construction shown in Figs. 8 to 65 13, the member 16 is provided on opposite

sides of its pivot with projections 23 and 24. A flange 25 on the member 15 contacts with the projecting part 23 as the member 15 swings upwardly. The member 15 has a threaded part 26 mounted upon the flange 25 and a nut 27 is screwed upon the threaded part. The nut is held in position by contact of the corrugations 28 upon it with a spring 29. Upon the downward motion of the member 15 the nut 27 engages the 70 projecting portion 24 on the member 16. The projection 30 on the operating bar en- gages within a slot 31 in the member 15 causing it to swing up and down as the em- 75 broiding mechanism is operated, and this 80 swinging or rotary reciproca- 85 tion is imparted to the member 16 in a proportion depend- ing upon the amount of lost motion respec- tively between the flange 25 and the part 23 and between the nut 27 and the part 24. 90 This proportion of the swinging of the mem- 95 ber 15 which is transmitted to the mem- ber 16 is dependent upon the position of the nut 27, and the reciproca- 100 tion or intermittent movement of the material contacting mem- ber 21 is thereby controlled.

In order to speed up my embroidering machine while it is guided by hand, I have provided, in the construction shown in Figs. 1 to 7, a source of power supply for the em- 95 broiding mechanism. A bracket 60 is clamped upon the guide 1 by means of screw 62 and held against twisting by the key 61. Projecting downwardly from the screw 62 is a threaded member 63 upon which is a nut 100 64 held between the ears 65, which are se- cured to the frame member 2. A disk 66 is journaled upon the bracket 60 and carries a gear face 67, which engages a pinion 68 also mounted on the bracket 60 and driven by a 105 flexible shaft 69 or an equivalent means. A block 70 fitting within a slot in the disk 66 is connected by a link 71 to the actuating member 10 and is movable within the slot by means of a screw 72 held in place by the col- 110 lar 73. In operating the embroidering ma- chine it is desirable that the needle shall never rise higher than the position shown in Fig. 1 and therefore when the block 70 is moved away from the center of the disk 66 115 to increase the extent of reciproca- 120 tion of the actuating member 10 and thereby cause the needle to be lifted as much above the position shown in Fig. 1 as its movement below that position is increased, it is necessary to unclamp the bracket 60 and draw it down by means of the nut 64.

In former embroidering machines the feeding has been effected by mounting the needle so that it will swing automatically as 125 it is pressed into the cloth or else providing means to swing the needle while it is in the cloth to effect the feeding of the machine. This movement of the needle out of its axial line separates the fibers of the material and 130

enlarges the hole produced by the needle and furthermore, it is not a positive and dependable feed and such a feeding could not be relied upon where the machine is speeded up to hundreds of stitches a minute.

It will therefore be seen that I have provided a machine in which the needle is moved only along its axial line and which is provided with a positive feeding mechanism capable of feeding the machine at any rate of operation.

In the construction shown in Figs. 1 and 2 the feeding means is drawn up clear of the material during certain portions of the stroke of the needle so that the machine may be twisted and turned to follow a pattern. It will also appear from what has been described that I have provided an embroidery machine embodying embroidery mechanism including a needle and the necessary mechanism for operating it and also including a feeding mechanism separate from the needle and which is operated from the embroidery means.

The embodiment of my invention herein described for the purpose of disclosing my invention, is a machine for making that class of embroidery wherein the stitches comprise loops of thread thrust through the material to a greater or less extent and at longer or shorter intervals. These looped stitches may be referred to as "turfing" but in forming the looped stitches the machine described does not necessarily employ a hollow quill-like needle such as that employed in numerous machines designated in the art by the title "Turfing machines." The looped stitches are not locked stitches and apparently are the usual type of stitch made by a machine which is adapted to be moved about over stretched material and having all its parts located on the same side of the material, the parts including a foot constituting the sole supporting means for the machine. A hand sewing machine making a locked stitch on the other hand has parts located on both sides of the material so as to produce a locked stitch and has a presser foot or the equivalent and a feeding member which grip the material between them.

While I have described my invention with considerable detail, I do not intend to be limited to the particular features and the constructions described, but intend that my invention shall be defined by the hereunto appended claims.

In the construction shown in Figs. 1 and 2 the amount of feeding for each stroke of the needle is varied by changing the proportion of the stroke of the feeding member 22 during which it rides upon the contact breaking member 58 so that in addition to securing the advantage of separating the feeding member 22 from the material while

the needle is in the material, the necessity is avoided for a lost motion construction such as shown in Figs. 8 to 13, and in my co-pending application, Serial No. 384,444, filed October 30, 1919, of which this application has been made to a certain extent a continuation.

What I claim and desire to secure by Letters Patent of the United States is:

1. In a hand embroidery machine, means 75 for forming looped embroidery stitches, and means other than said stitch forming means for feeding the machine.

2. In a hand embroidery machine, means for forming looped embroidery stitches, and 80 additional means operated thereby for feeding the machine.

3. In a hand embroidery machine, a frame having a foot constituting the sole supporting means for the machine, stitch forming 85 means and means other than said stitch forming means for feeding the machine.

4. In a hand embroidery machine, a frame having a foot, stitch forming means, and feeding means other than said stitch forming means and operable in the production 90 of its feeding effect independently of the pressure of said foot against the material to be embroidered.

5. In a hand embroidery machine, means 95 for forming looped embroidery stitches, and means for feeding the machine on the back stroke of the stitch forming means.

6. In a hand embroidery machine, means for forming looped embroidery stitches, and 100 means including a member adapted to contact with the material to be embroidered to feed the machine and means for breaking such contact while the stitch forming means engages the material.

7. In a hand embroidery machine, means for forming looped embroidery stitches, and means for feeding the machine, including a member for engaging the material to be embroidered and means for reciprocating 110 said member to effect the feeding action.

8. In a hand embroidery machine, means for forming looped embroidery stitches including a needle and means for holding said needle against movement out of and reciprocating it in its axial line, and means 115 other than said stitch forming means for feeding the machine.

9. In a hand embroidery machine, means for forming looped embroidery stitches including a needle and means for holding said needle against movement out of, and reciprocating it in its axial line, means other 120 than said stitch forming means for feeding the machine, and power driven means for operating the machine.

10. In a hand embroidery machine, means for forming looped embroidery stitches, including a needle and means for reciprocating it along its axial line and means other 125

- than said stitch forming means for feeding the machine.
11. In a hand embroidering machine, stitch forming means, a feed member having a portion for engaging the material to be embroidered, means for actuating said member, and a part on to and off of which said portion slides respectively out of and into engagement with the material to be embroidered. 70
12. In a hand embroidery machine, means for forming looped embroidery stitches, feeding means comprising a resilient part actuated by its resilience toward and directly contacting the material to effect the feed, and means for actuating said feeding means. 75
13. In a hand embroidering machine, stitch forming means, a resilient feed member having a portion for engaging, and actuated by the resiliency of said member toward, the material to be embroidered, means for actuating said member and a part on which said portion slides during a portion 80 of its movement.
14. In a hand embroidering machine, stitch forming means, a resilient feed member having a portion for engaging, and actuated by the resiliency of said member toward, the material to be embroidered, means for actuating said member, and a part on to and off of which said portion rides respectively out of and into engagement with the material to be embroidered. 85
15. In a hand embroidery machine, stitch forming means, a feed member, means for actuating said member, and a part fixed during operation of the machine upon which said member slides into and out of contact with the material to be embroidered. 90
16. In a hand embroidery machine, stitch forming means, a feed member, means for actuating said member, and a part upon which said member slides into and out of contact with the material to be embroidered. 95
17. In a hand embroidery machine, stitch forming means, a feed member, means for actuating said member, means normally tending to move said feed member toward the material to be embroidered, and a part fixed during operation of the machine upon which said member slides into and out of contact with the material to be embroidered. 100
18. In a hand embroidering machine, a frame, embroidering means including a needle mounted thereon, a movable member for feeding by contact with the material to be embroidered and a member on said frame upon which said feeding member rides out of engagement with the material during a portion of its movement in a direction to effect the feeding. 105
19. In a hand embroidering machine, a frame, embroidering means including a needle mounted thereon, a movable member for feeding by contact with the material to be embroidered and a member on said frame upon which said feeding member rides out of engagement with the material during a portion of its movement in a direction to effect the feeding. 110
20. In a hand embroidery machine, stitch-forming means, and feeding means including a reciprocable member and means for adjusting the initial position of said member independently of the length of stroke thereof. 115
21. In a hand embroidery machine, means for forming looped stitches and a material-contacting feeding means, said stitch-forming and feeding means being independently adjustable. 120
22. In a hand embroidery machine, stitch-forming means, a feeding member, means for actuating said feeding member and means comprising a part on which said member slides for breaking contact between said member and the material to be embroidered by the reciprocation of said member. 125
23. In a hand embroidery machine, stitch-forming means, a feeding member, means for actuating said feeding member and means for breaking contact between said member and the material to be embroidered by the reciprocation of said member. 130
24. In a hand embroidery machine, stitch-forming means, a feeding member, means for actuating said member from said stitch-forming means, and a part upon which said member slides out of contact with the material to be embroidered at a point in the operation of said stitch forming means. 135
25. In a hand embroidery machine, stitch-forming means, a feeding member, means for actuating said feeding member from said stitch-forming means, and a part upon which said member slides out of contact with the material to be embroidered as said stitch-forming means approaches its advanced position. 140
26. In a hand embroidery machine, means for forming looped embroidery stitches, feeding means including a member for contacting with the material to be embroidered and means for breaking contact between said member and the material to be embroidered at a certain point in the operation of said stitch-forming means. 145
27. In a hand embroidery machine, means for forming looped embroidery stitches and feeding means including a member for contacting the material to be embroidered and means for intermittently moving said member in a direction to feed the machine. 150
28. In a hand embroidering machine, means for embroidering including a foot having an opening therein and feeding means including a member for contacting with the material to be embroidered through said opening. 155

29. In a hand embroidering machine, means for embroidering including a foot, and feeding means including a resilient member movable in a plane substantially parallel with the material to be embroidered and biased toward said material by its resilience. 5
30. In a hand embroidering machine, embroidery means, a feeding member, means for moving said member in two directions in contact with the material to be embroidered and means for making and breaking such contact. 10
31. In a hand embroidering machine, a frame, embroidery means mounted thereon, and feeding means including two members mounted on said frame for reciprocation and respectively having parts engaging during reciprocation, one of said parts being adjustable relatively to the part on which it is positioned. 15
32. In a hand embroidering machine, embroidery means including a needle, and feeding means including two links pivoted together, one of said members having a notched part adjustably mounted thereon and the other of said members having a finger extending into said notch. 20
33. In a hand embroidering machine, a frame, embroidery means including a needle mounted thereon, a movable member for feeding by contact with the material to be embroidered, and means for moving said member including two links and means for adjusting the angular relation of said links. 25
34. In a hand embroidering machine, a frame, embroidery means, including a needle mounted on said frame, a bracket on said frame, a geared member mounted in said bracket and operatively connected to 40 said embroidery means and a second gear mounted on said bracket and engaging said first gear and provided with means for receiving power. 45
35. In a hand embroidering machine, means for embroidering, including a foot, and additional means for feeding the machine, said feeding means and foot engaging the same surface of the material to be embroidered. 50
36. In a hand embroidering machine, means for embroidering and additional means for feeding the machine, all parts of the machine being positioned during operation on the same side of the material to be 55 embroidered.
37. In a hand embroidering machine, means for forming unlocked embroidery stitches and means other than said stitch forming means for feeding the machine. 60
38. In a device of the class described, a frame including a supporting foot, a member mounted in said frame for reciprocation and having means for attaching a needle thereto, a member pivoted to said frame, a resilient feeding member secured to said last named member, and actuated by its resilience toward the same surface of the material to be embroidered as that engaged by said foot, a second member pivoted to 65 said frame for movement about its pivot by said reciprocating member, and means for varying the angular relation of said two members pivoted to said frame. 70
- In testimony whereof, I have signed my 75 name to this specification.

ABRAHAM BALINKY.
